UNITED STATES PATENT OFFICE

99,513

DESIGN FOR A BATTERY BOX

Raymond Le Clercq, Los Angeles, Calif.

Application January 25, 1936, Serial No. 60,800

Term of patent 14 years

To all whom it may concern:

Be it known that I, Raymond Le Clercq, a citizen of the United States, residing at Los Angeles, in the county of Los Angeles and State of California, have invented a new, original, and ornamental Design for a Battery Box, of which the following is a specification, reference being had to the accompanying drawing forming part thereof.

Fig. 1 is a top plan view.

Fig. 2 is a front elevation.

Fig. 3 is a side elevation of one end of the box, the opposite end having the same appearance.

Fig. 4 is a rear elevation of a battery box showing my new design.

I claim:

The ornamental design for a battery box as shown and described.

RAYMOND LE CLERCQ.
